UNITED STATES PATENT OFFICE.

MAUD WYMAN, OF OAKLAND, CALIFORNIA.

SLATE ATTACHMENT.

SPECIFICATION forming part of Letters Patent No. 450,092, dated April 7, 1891.

Application filed September 13, 1890. Serial No. 364,921. (No model.)

To all whom it may concern:

Be it known that I, MAUD WYMAN, of Oakland, in the county of Alameda and State of California, have invented a new and useful 5 Improvement in Slate Attachments, of which the following is a specification.

My invention is an improvement in the class of educational appliances or apparatus in which a series of endless bands or tapes 10 bearing numbers or letters of the alphabet are arranged on rollers or shafts within a box having an opening through which a particular portion of the said bands may be seen.

My invention is embodied in the construction and combination of parts hereinafter described and claimed, whereby I provide an improved apparatus for use of pupils in learning to write or draw such letters or characters as may be applied to the endless bands. 15 I employ a slate and arrange the lettered bands to run beneath it and through slots in its frame and also over a portion of the latter, so that any particular characters on the bands may be brought prominently to view; 20 and I also provide spring-clamps, which press the bands upon the slotted frame, through and over which they pass, so that by manipulating a particular clamp any individual band may be readily released when it is desired to 25 move it along for the purpose of bringing another letter or other character to view.

In the accompanying drawings, Figure 1 is a plan view of my improved apparatus, part being broken out. Figs. 2 and 3 are cross sections on lines 2 2 and 3 3, respectively, of 30 Fig. 1.

A slate 10 is fixed in the upper side of a box 11, and within the latter at its upper and lower sides are located two parallel shafts 12 and 12^a. A series of endless bands 16 run on these shafts, and the latter are provided with a series of circumferential flanges 13 to keep the bands separated from each other. It will 35 be understood that the flanges of one shaft

are directly opposite those of the other shaft. 45 Each shaft has a pulley 14, and an endless cord 15 runs on the same, it being wound one or more times around each pulley to prevent slipping.

A disk 18 is fixed on one end of the upper 50 shaft 12 and projects above the top surface of the box 11, so that it is easily visible and also conveniently accessible. By applying a finger to the said disk 18 the shaft 12 may be rotated, and through the medium of the cord 55 15 the other shaft is rotated also, whereby the endless bands 16 are moved correspondingly. These bands are provided with letters of the alphabet or other characters, which become successively visible as the bands pass over 60 the bar 17, and may therefore be conveniently copied on the slate 10.

The bands are held normally immovable by means of spring-clamps 20, attached to the bar 19 at the upper side of the box 11. By 65 pressing a particular clamp backward the band on which it bears is released, so that it may be moved along to bring another character into view. The characters to be copied are always prominently exposed to the eye of 70 the pupil, and the bands may be easily moved to change them as desired. The slate forms one side of the box, which incloses and protects the moving parts save the spring-clamps.

What I claim is—

The combination, with the box 11, the slate 75 10, its upper frame-bar 17, having diagonal slots 17^a, and the shafts 12 and 12^a, disk 18, cord, and pulleys, of the series of endless letter-bearing bands, and spring-clamps mounted 80 on the upper portion of the frame and pressing the bands that pass through the said slots upon the adjacent upper portion of the frame-bar, as shown and described.

MAUD WYMAN.
